UNITED STATES PATENT OFFICE

2,334,484

ACOUSTICAL ASSEMBLY

James Y. Dunbar, New York, N. Y., assignor to
Johns-Manville Corporation, New York, N. Y., a
corporation of New York

Application July 6, 1939, Serial No. 282,961

19 Claims. (Cl. 189—85)

The present invention relates to acoustical assemblies, and particularly to lighting units to be employed therein.

An acoustical treatment for walls, such as ceilings, and the like which has achieved outstanding commercial success is disclosed in patent to Norris No. 1,726,500, issued August 27, 1929, the treatment including a perforated facing element behind which is disposed a sound-absorbing medium. The facing element preferably takes the form of a plurality of metal pans including vertical edges supported from the wall, the pans containing individual fibrous sound-absorbing pads. The facing elements lie in substantially the same plane and form the visual wall of the room to which the treatment is applied.

Prior to the instant invention lighting fixtures of conventional type have been employed with acoustical treatments as described above, such lighting fixtures normally being affixed to the inner ceiling or other base member and passing through the acoustical treatment. The conventional types of fixtures have not, however, presented the flexibility of arrangement, uniformity of appearance, and other features desired.

An object of the instant invention is to provide an acoustical system including lighting units as a unitary part thereof.

Another object of the invention is the provision of an acoustical construction, particularly of the type as disclosed in the Norris patent referred to above, including means for the substitution of lighting fixtures for acoustical units in any desired portion of the treatment.

A further object of the invention is the provision of an acoustical treatment including lighting fixtures of a character to permit the ready rearrangement of the lighting fixtures as may be desired from time to time.

A further object of the invention is the provision of an acoustical treatment including lighting fixtures, the treatment presenting a substantially uniform and attractive appearance.

A still further object of the invention is the provision of a lighting fixture to be employed in conjunction with acoustical treatments, the fixture including elements arranged to be supported in substantially the manner that the acoustical units are supported.

Briefly described, my invention resides in the provision of a supporting means comprising, either in whole or in part, the conventional support for the pans of acoustical units of the type referred to, and a lighting fixture including a lens element of a character to be supported by a

said means in a similar manner to the acoustical units. The lighting fixtures include leads for connection to electrical outlets placed at accessible locations above the treatment. The lighting fixtures may be substituted in any desired arrangement for acoustical panels and may be rearranged as often as desired to obtain advantageous lighting of a room. Thus, a construction in accordance with the invention permits a concentration of the lighting fixtures as may be desired upon one occasion and the rearrangement or distribution of the same as may be required upon another.

My invention will be more fully understood and further objects and advantages thereof will become apparent when reference is made to the more detailed description thereof which is to follow and to the accompanying drawings, in which

Fig. 1 is a perspective view of a partial room interior, including a combined acoustical treatment and lighting means in accordance with the present invention;

Fig. 2 is a perspective view with parts broken away looking downwardly upon the acoustical treatment and lighting means of the room of Fig. 1;

Fig. 3 is a sectional view taken on the line 3—3 of Fig. 1;

Fig. 4 is a face view of assembled acoustical and lighting units of the present invention;

Fig. 5 is a plan view of a portion of the construction of the present invention;

Fig. 6 is a perspective view of an element of a lighting unit of the present invention;

Fig. 7 is a perspective view of a catch bar employed with the element of Fig. 6;

Fig. 8 is a detail view with parts broken away of the catch and catch bar construction;

Fig. 9 is a sectional view taken on the line 9—9 of Fig. 4; and

Fig. 10 is a view similar to Fig. 3, illustrating a slightly modified form of the invention.

Referring now to the drawings, and particularly to Figs. 1 and 2, a basically conventional acoustical treatment is disclosed, including generally the construction of the previously referred to Norris, Pat. No. 1,726,500. As shown in Fig. 2, the treatment is supported from the inner ceiling or wall of the room by members 10 carrying longitudinally extending attaching members 11 or T-bars 12. The T-bars (see particularly Fig. 5) comprise a base 14 and resilient converging side flanges 16 including locking lips 18. The said ends easily slidably enter the ends of the side flanges and resiliently maintain their position until they are locked in place by the locking lips 18.

T-bars are formed of any suitable light gauge metal.

The acoustical treatment comprises a plurality of shallow metal pans 20 including upstanding side walls having an integral bead 24. Each pan contains a pad 22 of a suitable sound-absorbing material such as mineral wool or the like. The lower or outer faces of the pans lie in substantially the same plane and form the visual surface of the ceiling or wall to which the treatment is applied. In the assembly of the acoustical units in the conventional manner, the beads 24 carried by the walls at the ends of the pans are forced or snapped into place between the lips 18 of the T-bars, whereby the units are securely but readily removably held in position. At the present time, the pans are commonly of a length substantially twice their width and are suitably demarcated by a transverse indentation or groove midway of their length on their outer face (see Fig. 4) to simulate two substantially square units. As will be understood, the center-to-center spacing of the T-bars will be equal to the lengths of the pans employed.

In accordance with the instant invention, means are provided to support a member including a lighting fixture in place of any one of the units 20. The lighting fixture may occupy the entire area previously occupied by an acoustical unit or only a portion thereof. Referring particularly to Figs. 3 and 4, a construction is illustrated in which elongated acoustical units are employed, namely, those which are substantially twice as long as they are wide and are divided by a groove to simulate two adjacent square units or tiles as previously referred to. Suitably, the lighting fixture takes the place of one of such simulated square units.

The lighting fixture comprises, as shown in Figs. 3 and 5, a frame 30 formed of angle members or the like of sufficient length to extend between and to partially overlap the bases 14 of adjacent T-bars. The frame includes lugs 32 adapted to be bent around the edges of the T-bar bases 14 to securely maintain the frame in position (see particularly Fig. 3). It will be understood that the frame 30 is made of a relatively lightweight metal or the like and the lugs 32 or equivalent means are readily bendable to permit the frame to be easily secured in and removed from its position on the T-bars. The frame 30 carries an auxiliary short T-bar 34 located approximately midway between the ends of the frame. The T-bar 34 may rest loosely on the horizontal flanges of the longitudinal frame members or may be secured thereto by welding or the like. T-bar 34 carries a positioning lug 38 which may suitably comprise an angle piece having one flange welded, riveted, or otherwise secured to the base flange of the T-bar.

A member, comprising a reflector or the like 38 and a bulb socket or similar means (not shown), is carried by the frame member and short T-bar 34, the reflector abutting against the upright flanges of the frame and the positioning lug 38, whereby the same is retained in proper position against sliding movement. Each of the lighting members includes an electric cable 40 and a plug 42 to be connected in an outlet 44 (see particularly Fig. 2). The outlets 44 are located in one or more suitable places above the acoustical treatment, whereby the same may be readily available for plugging in lighting fixtures wherever located.

The lighting fixture also includes a lens frame 46 (see particularly Figs. 3 and 6) comprising vertical members 48 and horizontal flanges 50, the latter supporting a lens 52 of any suitable or conventional type. Two or more of the vertical members 48 carry abutment members 54 for securing the lens 52 in position within the lens frame. One wall 48 carries a hinge 56 having a leaf 58 secured by welding or the like to the wall and the other leaf 60 extending substantially the height of the frame and including a locking bead 62, similar to or the same as that carried by the flanges of the acoustical pans previously referred to. The wall 48 of the lens frame opposite to that carrying the hinge 56 has locking lugs 64 secured thereto by welding or the like (see particularly Figs. 6, 8, and 9).

A catch bar 70 is provided (see Fig. 7) comprising an upright flange 72 and a base flange 74, the latter preferably being suitably reinforced, for example, by folding back the metal of the bar as shown. The catch bar includes notches 76 for cooperative interlocking engagement with the members 64, as most clearly shown in Figs. 8 and 9. The upright flange 72 of catch bar 70 includes an extending bead 78 similar to or the same as that provided on the hinge 56 and the flanges of the acoustical pans.

In the assembly of an acoustical treatment including lighting fixtures as a unitary portion thereof, in accordance with the instant invention, the acoustical pans 20, if previously mounted, are removed from the locations where the lighting fixtures are desired. The removal is accomplished in the conventional manner and requires merely the pulling down of the pans to unsnap the beads on their flanges from the T-bars. A frame member 30 is then inserted to overlie each location previously held by an acoustical pan and is secured in position by bending the lugs 32 around the edges of the base flanges 14 of the T-bars. The reflector 38 is then placed in position with its edges confined by the upright flanges of the frame elements and the lug 36, and plug 42 connected to an adjacent outlet 44. An acoustical unit 82, substantially similar in every detail to the conventional units except that it is made of a length to correspond to the distance between the T-bar 12 and the short T-bar 34, is inserted as illustrated in Fig. 3. Catch bar 70 is snapped into position with its bead 72 engaging a lip of the short T-bar 34, and leaf 60 of hinge 56 is similarly inserted in the conventional fixed T-bar 12 (see Fig. 3). If desired, the positions of the lens frame and catch bar may be reversed, the hinge leaf 60 being inserted in the T-bar 34 and the catch bar in the T-bar 12. An electric bulb or other lighting means, if not previously inserted, may then be screwed into the socket (not shown) within the reflector 38 and the lens member swung upwardly on its hinge until the snap members 64 cooperate with the notches 76 in the catch bar to secure the lens in closed position. The lens may be readily opened at any time for replacing the electric bulb or the like, by pressing inwardly on the catches 64 through the notches 76 of the catch bar, as will be readily understood from an examination of Fig. 9.

The construction in accordance with the invention as described above permits the positioning of the lighting fixtures in any desired arrangement. The changing of the positions of the lighting fixtures merely requires the removal of the lens frame 46 and of the acoustical unit 82, and dis-

connection and removal of the reflector unit 38 and frame 30. All this can be readily done without any great degree of care or skill. The conventional acoustical unit is then removed from the location where the lighting unit is to be inserted and the lighting unit assembled in position as previously described, the acoustical unit being snapped into position in the location formerly occupied by the lighting unit.

As shown in Fig. 10, the lighting fixture may occupy the entire space between the conventional fixed T-bars if desired. This construction may be employed, for example, if square, rather than the two element simulating acoustical units, are employed, or if a relatively large lighting fixture is desired. The construction disclosed in Fig. 10 is similar to that previously described, except that the lighting unit and reflector occupy the entire space within the frame 34, the short T-bar being not required. The lens frame and catch bar are preferably of the same types as those previously described.

An acoustical construction in accordance with the invention, in addition to having the advantages of ready arrangement and rearrangement of the lighting units, exhibits the further feature of uniformity in appearance of the ceiling or wall to which the treatment is applied and the elimination of projections from the treatment. As a result, a very attractive ceiling or wall construction is obtained, together with an arrangement of lighting as may be desired for any particular use or occasion. The lighting fixtures may be made of any size desired and may be made, for example, to occupy the space where any number of acoustical units are normally employed. Also, any desired arrangement may be employed to provide ornamental effects such as bars or rows of lighting fixtures or to direct the light to any part of a room.

If desired, types of lighting may be employed other than the conventional reflector and bulb described. Thus, for example, fixtures may be employed which are wholly contained within the lens frame, with a resulting simplicity of construction and a reduction in the number of parts required.

Having thus described my invention in rather full detail, it will be understood that these details need not be strictly adhered to, but that various changes and modifications will suggest themselves to one skilled in the art, all falling within the scope of the invention as defined by the subjoined claims.

What I claim is:

1. A partition comprising a base, a plurality of supporting bars suspended therefrom, said bars lying in substantially parallel relationship to one another, a plurality of interchangeable units detachably supported by said bars and bridging the spaces therebetween, certain of said units comprising pan-like members and a sound-absorbent filler therefor, and others of said units including a lighting fixture carrying a source of illumination and comprising an inverted reflector, said fixture having a substantially uninterrupted light transmission zone underlying the reflector and a lens coextensive with said zone.

2. A partition comprising a base, a plurality of T-bars suspended from said base and lying in substantial parallelism to one another, a plurality of perforated pan-like members containing a sound-absorbent pad detachably supported from said T-bars and bridging the spaces therebetween, and units interspersed with said pan-like

members and each including a lighting fixture carrying a source of illumination, the lighting fixture including an inverted reflector and having a substantially uninterrupted light transmission zone underlying the reflector, said units being detachably supported by said T-bars.

3. A partition comprising a base, a plurality of T-bars suspended from said base and lying in substantial parallelism to one another, a plurality of perforated pan-like members containing a sound-absorbent filler supported from said T-bars and bridging the spaces therebetween, and units interspersed with said pan-like members and each including a frame supported on said T-bars, a short T-bar carried by said frame, a pan-like member including a sound-absorbent filler supported from one of said first-mentioned T-bars and said last-mentioned T-bar, and a lighting fixture including a lens member supported from said last-mentioned T-bar and another of said first-mentioned T-bars, and a reflector supported by said frame.

4. A lighting fixture supported on substantially parallel supporting members of an acoustical treatment comprising a frame having opposite ends resting on spaced ones of said supporting members, a supporting element carried by said frame and extending transversely thereof, a reflector supported on said frame and a lens member including opposite ends detachably engaged with one of said supporting members and said supporting element, respectively.

5. A lighting fixture supported on substantially parallel supporting members of an acoustical treatment comprising a frame having opposite ends resting on spaced ones of said supporting members, a supporting element carried by said frame and extending transversely thereof, a reflector supported on said frame, means on said frame and said supporting element for maintaining said reflector against movement on said frame, an acoustical unit carried by said element and one of said members and a lens member including means at opposite ends detachably engaged with the other of said supporting members and said supporting element, respectively.

6. A lighting fixture supported on substantially parallel supporting members of an acoustical treatment comprising a frame having opposite ends resting on spaced ones of said supporting members, a supporting element carried by said frame and extending transversely thereof, one of said supporting members and said supporting element defining a supporting means, and a lens member carried by said supporting means, said lens member comprising a frame, a hinge carried by said frame and including a leaf detachably connected to said supporting means, a catch bar detachably connected to said supporting means, and interlocking means between said frame and catch bar.

7. A lighting fixture supported from parallel supporting members of an acoustical treatment comprising a frame having opposite ends resting on spaced ones of said supporting members, a reflector resting on said frame, and a lens member detachably supported at opposite edges by one of said parallel supporting members and said frame, respectively.

8. A lighting fixture supported from parallel supporting members of an acoustical treatment comprising a frame having opposite ends supported on spaced ones of said supporting members, a reflector resting on said frame, and a lens member having opposite ends interlocking en-

gaged with said spaced ones of said supporting members.

9. A wall comprising a base and a facing therefor, said facing comprising a plurality of acoustical units and lighting fixtures, said lighting fixtures including inverted reflectors and carrying a light source, said fixtures having substantially uninterrupted light transmission zones underlying said reflectors, said units and fixtures including outer faces lying in substantially a single plane, and means including members suspended from said base for interchangeably supporting said units and fixtures.

10. A wall comprising a base, a plurality of acoustical units and lighting fixtures forming a facing for said base, each of said lighting fixtures including an inverted reflector and carrying a light source, said fixtures having substantially uninterrupted light transmission zones underlying said reflectors, means for supporting said units and fixtures including members supported from said base and means detachably interlocking said units and fixtures to said members.

11. A partition comprising a base, a supporting structure suspended therefrom, a facing comprising a plurality of acoustical units and lighting fixtures, each of said lighting fixtures including an inverted reflector and carrying a light source, said fixtures having substantially uninterrupted light transmission zones underlying said reflectors, each of said units and fixtures including attaching flanges, and means for detachably interlocking said flanges to said supporting structure.

12. A combined ceiling and lighting appliance comprising a plurality of fixed parallel supporting elements each having a dependent clip, a plurality of rectangular tiles, each having upwardly extending attaching means at opposite ends and receivable by the clips for detachably securing the tiles in place to form the dominant ceiling area in which an opening without any tile may be had at any selected place in the ceiling area, a frame spanning the supporting elements above the opening, a downwardly acting reflector supported by the frame above the level of the tiles, a light source in the reflector, a light transmitting screen opposite the mouth of the reflector and disposed substantially in the plane of the ceiling, and screen supporting means including a frame having on one edge thereof attaching means cooperative with the clip of one of the supporting elements, and devices for supporting the opposite edge of the screen supporting frame from the reflector supporting frame, the width of the screen supporting frame being equal to the width of a tile.

13. A combined ceiling and lighting appliance comprising a plurality of fixed parallel supporting elements each having a dependent clip, a plurality of rectangular tiles, each having upwardly extending attaching means at opposite ends and receivable by the clips for detachably securing the tiles in place to form the dominant ceiling area in which an opening without any tile may be had at any selected place in the ceiling area, a frame spanning the supporting elements above the opening, a supplemental supporting element similar to and parallel with the first named supporting elements secured midway of the spanning frame to form two square openings, a tile similar to the other tiles occupying one of the square openings and similarly secured between adjacent supporting elements, a down-

wardly acting reflector supported by the spanning frame over the second opening, a light source in the reflector, and a screen supporting means including a frame having attaching means similar to those of the tiles and received in the clips at the opposite sides of the second opening.

14. The combination with a ceiling having fixed supports and a plurality of interchangeable rectangular tile downwardly removable therefrom and normally covering the entire surface of the ceiling, of a luminaire, comprising a light source, a downwardly acting reflector, and a light transmitting screen opposite the mouth of the reflector, and luminaire supporting means comprising a rectangular screen supporting frame downwardly removably supported from the fixed supports, disposed substantially flush with the ceiling surface and of a size to occupy the entire width of the opening provided by the removal of a tile, and a reflector support carried by the fixed supports and disposed above the same.

15. In a tile ceiling having parallel dependent clips and tiles whose length is twice the breadth supported at their ends from the clips by concealed supporting elements and disposed about a rectangular opening, a frame spanning the opening and supported above the clips, a downwardly acting reflector supported by the frame above the level of the tiles, a light source in the reflector, a rectangular frame insertible into said opening and having on two opposite ends thereof clip cooperative elements similar to those of the tile, and a light transmitting screen secured therein.

16. A wall comprising a base and a facing therefor, said facing comprising a plurality of units and lighting fixtures, said lighting fixtures including inverted reflectors and carrying light sources said fixtures having substantially uninterrupted light transmission zones underlying said reflectors, said units and fixtures including outer faces lying in substantially a single plane, and means including members suspended from said base for interchangeably supporting said units and fixtures.

17. A ceiling or the like comprising a superstructure, a plurality of parallel supporting bars spaced at modular intervals and suspended therefrom at a common level, a plurality of flat rectangular ceiling block members of modularly related size bridging certain of the spaces between the supporting bars and detachably supported by the bars to form a facing in a single plane and leaving unoccupied certain other spaces of modularly related size, and supplemental members of modularly related size occupying the space left vacant by the omission of one or more ceiling block members and including down lighting apparatus, said apparatus carrying a light source and having an outer face, said supplemental members being detachably supported from said bars in position to have their outer faces including the outer faces of the lighting apparatus lie in substantially the single plane of the facing, all the members in their entirety concealing the bars and their suspension from the superstructure.

18. A combined ceiling and lighting appliance comprising a plurality of fixed parallel supporting elements each having a dependent clip, a plurality of rectangular tiles, each having upwardly extending attaching means at opposite ends and receivable by the clips for detachably securing the tiles in place to form the dominant ceiling area in which an opening without any tile may

be had at any selected place in the ceiling area, a frame spanning the supporting elements above the opening, a supplemental supporting element similar to and parallel with the first named supporting elements secured midway of the spanning frame to form two square openings, a tile similar to the other tiles occupying one of the square openings and similarly secured between adjacent supporting elements, a downwardly acting reflector supported by the spanning frame over the second opening, a light source in the reflector, a screen supporting frame having attaching means similar to those of the tiles and received in the clips at the opposite sides of the second opening, a hinged frame in the screen supporting frame, and a flat screen in the hinged frame which completely closes the opening.

19. A partition comprising a base, a plurality of T-bars suspended from said base and lying in substantial parallelism to one another, a plurality of block members supported from said T-bars and bridging certain of the spaces therebetween, and units interspersed with said block members and each including a frame supported on said T-bars, a short T-bar carried by said frame, a smaller block member supported from one of said first-mentioned T-bars and said last-mentioned T-bar, and a light controlling screen supported from said last-mentioned T-bar and another of said first-mentioned T-bars, and a reflector supported by said frame above the screen.

JAMES Y. DUNBAR.
